ABSTRACT: Photoelectric device for the automatic correction of the lamp carbons of projectors. A lamp has two photoelectric cells and an appropriately diaphragmed lens located laterally of the lamp in front of the arc of light and spaced so as not to be damaged by the heat. The amplified image from the carbons is projected onto the two photoelectric cells which are sensitive to the light of the arc. Two photoelectric relays are provided acting independently, one for the positive carbon and one for the negative carbon, so that they send the respective effects of their sensitivity to each one of the two photoelectric cells. An electromagnet having a solenoid is activated by the relays located in the advancing speed variator of the carbons, comprising means for correcting the malformed crater caused by combustion in the positive carbon and the negative carbon. A guiding support for the negative carbon maintains such carbon in an exact position in relation to the positive carbon. The negative carbon carrier is slightly movable in its vertical position as well as in its horizontal position, so that the advancing of the negative carbon may be done without difficulty.

PHOTOELECTRIC DEVICE FOR AUTOMATICALLY CORRECTING THE CARBONS OF PROJECTORS

This invention furnishes the means for achieving automatic stabilization and uniformity in the arc lamp consumption of the positive carbon, and to prevent the malformed crater which invariably appears on the electrode itself.

There are units which automatically regulate the optimum distance between the electrodes in such a way that they advance as natural consumption occurs. Thus, they maintain the proper distance and also the focal point of the lamp since the positive and negative carbons have their own independent means of propulsion. These are generally automated by utilizing photoelectric cells or any other type of device sensitive to light from the arc lamp. Thus, for example, varying resistance when a photoelectric cell receives light transmits its effect to appropriately located relays which act on the carbons being consumed. However, in practice it has been proven that employment of such regulating devices does not prevent the serious drawback resulting from the malformation or crater which originates on the negative carbon as it is consumed. This is detrimental to the function of the luminous projector since it is highly advisable that consumption of the positive carbon be as regular as possible. Consumption should be maintained on a plane perpendicular to the longitudinal axis of the carbon. An object of the invention is to remove the above disadvantages.

Insofar as to closeness of the carbons, the device may be any one of the known types. For example, those constituted on the basis of a lens located on the side of the lamp which receives the image from the carbons and, adequately enlarged, projects it on two photoelectric cells which upon being illuminated act upon relays or speed changers which advance the electrodes and thus maintain the focal point and regulation of the arc.

The correcting device to which this invention relates is particularly designed to act in collaboration with the aforementioned system for bringing the electrodes together. Basically, it consists of several photoelectric cells which function to change the position of the carbons facing each other in the horizontal and vertical. In this manner a possible deformation of the positive carbon crater is corrected.

With the above and other objects in view which will become apparent from the detailed description below, some preferred embodiments of the invention are shown in the drawings, in which:

FIG. 1 is a schematic view showing the positive and negative carbons resting on their corresponding bases.

FIG. 2 is a similar view showing the location or status of the correcting elements when the consumption of the positive electrode occurs without deformation.

FIG. 3 is a schematic view showing the formation of a vertical crater on the positive electrode, with greater consumption in the higher area of the carbon.

FIG. 4 is a similar view also showing a malformation of the positive carbon which is vertical. In this case there is a higher degree of consumption in the lower area of the carbon.

FIG. 5 is a schematic view of a modification in the correcting devices shown in the foregoing figures.

In FIG. 1 a base 8 supports the negative carbon and is similar to the base 9 for the positive carbon. This base-guide 8 maintains the proper position of its carbon with relation to the positive and independent negative carbon, whether in a straight line or not.

The negative carbon holder will be mechanized to its base in such a way that it can pivot slightly either horizontally or vertically in order that the negative carbon, supported on its guide, may effortlessly advance.

Automatic correction of the crater will be effected in two positions: vertical and horizontal. For the first position—FIG. 2—the carbon image is taken from the L lens horizontally, cooperating with the two cells 10 and 11. These cells independently transmit their effects to relays 10' and 11'. The relays in turn transmit continuous current to a double coil 12

horizontally located in front of the luminous arc 5 in such a way that the magnetic effect of its iron nucleus 13 reaches the arc 5. It functions as follows:

As shown in FIG. 2 no cell is active since the carbons are in proper position. Consequently relays 10' and 11' are open and no current passes to the coil 12. Supposing that nothing carbon is consumed in a regular fashion, all the cells 10 and 11 go into action. They activate their respective relays 10' and 11' which circulate a continuous current through the double coil 12 in the direction indicated by arrows. As will be noted these are the same but go in different directions, their magnetic effects are cancelled and nothing happens.

Let us now suppose that for any reason the positive carbon is consumed according to FIG. 3. The cell 10 is then activated and therefore its relay 10', while relay 11' remains open because the cell 11 is in darkness. In this case current circulates only through the double coil 12 in one winding only as shown by the arrow. It magnetizes the iron nucleus which influences its action on the electric current originating the arc according to electrodynamic laws and perpendicularly shifts the magnetic flow in one direction or another, depending upon magnetic polarity (in this case downward). It more intensely attacks part a of the carbon to a point where it is consumed and the crater corrected, thus letting light into the cell 11. This activates the relay 11' from which current passes to the other coil which, as has been stated, is in an opposite direction, and its effects compensated. Thereby magnetism in the nucleus is cancelled. Also, as the cell 10 is darkened, it disconnects the relay 10' and is left without current.

Let us again suppose that the crater is formed vertically but in an opposite direction as shown in FIG. 4. The cell 11 activates the relay 11', while relay 10' is open because its cell 10 is in darkness, current circulating through half of coil 12 as indicated by the arrow, however in a direction opposite to that shown in FIG. 3. The nucleus therefore magnetizes but its polarity is contrary to the above case and the effect on the current of the arc is also in reverse of the above. It is shifted upward and consequently will more intensely attack part b of the positive carbon until consumption is equaled as in the foregoing case. This device permits correction of the crater in both vertical directions of the carbon at top and bottom.

Everything is the same as in the preceding case when correcting the two horizontal directions, right and left, of the crater. With a similar device not shown we take the image from the carbons vertically from the top. The coil is placed vertically also, under the arc as indicated in FIG. 1, to the side of the base of the positive carbon guide.

It may be that the deformed crater surface be inclined; that is to say, it is neither vertical nor horizontal. Then both activating devices operate simultaneously on the point where correction is necessary.

The crater may also be corrected as shown in FIG. 5. An electrically insulated crank 15 is placed on an axle 14 behind reflecting mirror 2 of the lamp. Part 15 passes by mirror 2 and approaches the negative carbon extreme end and serves as a guide-base therefor. Part 16 of the iron, goes through the interior of a coil 17 until it faces the north and south poles of another coil 18 with double coil. A spring 19 keeps the crank 15-16 steady and centered between poles north and south.

Operation is as follows: As previously explained, when the crater of the positive electrode activates the cells which have been placed over its image for correction and the respective relays are activated, these transmit the current to the coil 18 and to the double coil relay 20. Both double coils are connected on a parallel and operate simultaneously.

When the crater is correct the respective cells activate their relays at the same time and there is no effect on the coil 18 nor on the relay 20, because the current in the two coils are equal and opposite. If the crater tends to deform, one of the cells will be in the light and the other in darkness. In this case there will be current in one branch only and consequently in half of the relay coil 20 which is then activated, shutting off the contacts 21. Likewise there will be current in one coil only 18 mag-

netizing its poles to the arm 16 with the indicated polarity. According to the laws of magnetism, poles of the same sign repel each other, while opposites attract. Therefore, the stick leaves its position and pushes the negative carbon upward until it corrects the crater, equalizing the light over both cells. The effect is deactivated both in the coil 18 and the relay 20. The latter stops passage of current to the coil 17 causing the magnetic force of the arm 16 to cease and it returns to its original position.

If we consider that the crater occurs in reverse to the foregoing, everything functions similarly. The relay 20 is activated and transmits current to the coil 17 and simultaneously to coil 18, therefore there is current in the coil. Since polarity is contrary to the above, the stick 16 shifts to the opposite, the negative carbon decreases and in correcting the crater of the positive carbon, everything returns to its original state.

The generic term "cells" has been employed throughout the description. It should be clarified that this refers to phototubes, photodiodes, phototransistors, etc., as well as to any other elements, which through incidence of infrared, red, blue, violet, ultraviolet, etc. radiations generate or modify electric, electromagnetic or electronic currents for corrections for which this invention is designed.

I claim:

1. Device for correcting a crater formed on the carbon electrode of an electric arc lamp comprising spaced carbon electrodes of an arc lamp, photoelectric cells, means for projecting the image of the ends of said electrodes adjacent the arc towards said cells, a support guide, a holder for the negative electrode mounted on said support guide to pivot universally so that said negative electrode may advance even when the linear facing position thereof changes with respect to the positive carbon electrode and means actuated by said cells controlling the pivoting of said holder.

2. Device according to claim 1 wherein correction of a positive carbon crater is made by placing an axle and insulated stick behind the reflecting mirror of the lamp which is beyond the mirror and approach the end of the negative carbon electrode to which it will serve as a guide-support, part of said stick faces the poles of a coil with double springs in which it is

centered by means of a spring for that effect, said assembly is disposed so that when a crater appears on the positive carbon electrode the cells will activate since they are placed so that said image activates the appropriate relay.

5 3. Device according to claim 1 wherein when the positive carbon consumption proceeds properly said image simultaneously activates predetermined cells, relays connected to said cells independently activated, a double coil located in front of the arc of light connected to said relays so that the magnetic effect of the nucleus of said coil reaches the arc whereby, as long as consumption of the positive carbon electrode is regular, no correction will occur since all the cells will be active and consequently because of opposition, their effect on said relays and coil is cancelled.

15 4. Device according to claim 3 wherein upon appearance of a vertical or horizontal crater on the positive carbon electrode its image is transmitted to a cell becoming active corresponding to the point where the crater has occurred, while the remaining cells remain in darkness, then only the relay functioning by said active cell will transmit current in one direction alone to one coil of said double coil so that its nucleus will be magnetized and its effect will influence the current producing the arc to flow perpendicularly to the correcting position which will depend upon the acquired polarity signal and the 20 positive carbon will be more intensely attacked on the side opposite the crater and the deformation is automatically corrected.

25 5. Device according to claim 4 wherein once automatic correction of the crater occurs, the cell which has been in darkness will be in the light because there has been a proper consumption of the positive carbon electrode, said last named cell activates the corresponding relay which will transmit current to the second coil so that the effect of the nucleus is cancelled and correction completed.

30 6. Device according to claim 5 wherein two groups of cells are provided to act independently in the correction of craters occurring either vertically or horizontally and which act jointly when the crater or malformation in the positive carbon electrode occurs in a mixed position when vertically inclined 40 and to one side.
